Primary Examiner — Keli L Hill*Assistant Examiner* — Karra S Johnson(74) Attorney, Agent, or Firm — Jeffrey P. Calfa; Mark C. Bach(57) CLAIM

The ornamental design for a truck vehicle, as shown and described.

DESCRIPTION

FIG. 1 is an isometric view of a truck vehicle showing our new design;

FIG. 2 is a top plan view of FIG. 1;

FIG. 3 is a left side view of FIG. 1;

FIG. 4 is a right side view of FIG. 1; and,

FIG. 5 is a front view of FIG. 1.

The broken lines showing environmental portions and features of the truck vehicle form no part of the claimed design.
